His Attorney.

UNITED STATES PATENT OFFICE.

ARTHUR MITCHELL, OF CHICAGO, ILLINOIS, ASSIGNOR TO MITCHELL-BENNETT COMPANY, A CORPORATION OF ILLINOIS.

GRINDSTONE ATTACHMENT FOR MEAT-CHOPPERS.

1,255,104.

Specification of Letters Patent. Patented Jan. 29, 1918.

Application filed May 15, 1916. Serial No. 37,712.

To all whom it may concern:

Be it known that I, ARTHUR MITCHELL, a citizen of the United States, and a resident of the city of Chicago, county of Cook, and State of Illinois, have invented certain new and useful Improvements in Grindstone Attachments for Meat-Choppers, of which the following is a specification.

My invention relates to improvements in 10 grind stone attachments for meat chopping machines, and has for its object the production of a device of this character, which will be of durable and economical construction and which will be capable of ready and expeditious attachment to a grind stone and as ready and easy detachment therefrom when desired.

Other objects will appear hereinafter.

The invention consists in the combinations 20 and arrangements of parts hereinafter described and claimed.

The invention will be best understood by reference to the accompanying drawings forming a part of this specification, and in 25 which,

Figure 1 is a partially sectional side elevation of a meat chopping machine equipped with a grind stone attachment embodying the invention,

Fig. 2 is a top plan view of the attachment detached, and

Fig. 3 is an end elevation of the bearing member and shaft included in the construction of the attachment.

The preferred form of construction as 30 illustrated in the drawings, is designed for use in connection with a conventional meat chopper either power or hand driven such as is in general use in butcher shops and like places. Such meat choppers comprise a housing 1 in which is rotatably mounted a worm 2. The end of the worm 2 at the discharge end of the housing 1 is formed with a stud 3 upon the squared portion 4 of which 35 are arranged the perforated cutters of the meat chopper when the latter is in use. In the employment of the attachment, these cutters are removed in order to adapt the chopper to accommodate the attachment.

The attachment comprises a tubular bearing member 5 having an annular flange 6 at 40 one end which is adapted to snugly fit in an annular seat 7 which is provided in the discharge end of housing 1. Said bearing member 5 is locked in operative relation with

the housing 1 by means of an annular keeper or flange 8 which is threaded upon the outer end of said housing and which is adapted to engage against the outer side of flange 6 as clearly shown in Fig. 1. In order to lock 60 the bearing member 5 against relative rotary movement, the flange 6 is formed at its upper side with a notch or slot 9 which is adapted for releasable engagement with the pin or projection 10 provided at the upper 65 side of seat 7.

In order to permit of the keeper or flange 8 passing over the flange 6 of the bearing member 5, said flange 7 is cut away at opposite sides as at 11, since with this arrangement one side of the keeper 8 may be first passed over the flange 7 and then the opposite side of said keeper rocked to position behind said flange. Without this arrangement, it is of course apparent that it would be impossible to pass the keeper 8 over the flange 6 inasmuch as the diameter of the opening in said keeper is less than the diameter of the flange 6.

Mounted in the bearing member 5 for rotary and longitudinal movement is a shaft 12 provided at its inner end with a socket 13 adapted for snug engagement with the stud 3 in order to operatively connect said shaft with the worm 2, so that when the latter is rotated, said shaft will be rotated therewith. Fixed to the outer end of shaft 12 is a circular grind stone 14. The shaft 12 is normally pressed toward the worm 2 in order to insure engagement of the socket 13 with the stud 3, by means of an elongated resilient yoke 15 engaging midway its ends against the outer end of shaft 12. In order to insure engagement of said yoke with said shaft, the former is provided with an opening 16 which is adapted for engagement with a pointed pin 17 projecting from said shaft as clearly shown in Fig. 1. The ends of said yoke 15 are connected by means of bolts 18 and coöperating nuts 19 with the ends of a cross piece 20, the central portion of which is secured by means of screws 21 with the outer end of bearing members 5. By this arrangement it will be seen that yoke 15 may be flexibly adjusted through 105 adjustment of nuts 19 in order to secure the desired pressure of said yoke upon the shaft 12.

The bolts 18 also serve as a support for a water pan 22 which is suspended there-

from, inclosing the lower portion of grind stone 14.

The attachment set forth is extremely simple and economical in construction, the same 5 may be readily and easily applied to a meat chopper or removed therefrom, and will be found highly efficient in use as in the sharpening of knives and cleavers of a butcher, or for any other purpose which a grind 10 stone may be employed.

While I have illustrated and described the preferred form of construction for carrying my invention into effect, this is capable of variation and modification without 15 departing from the spirit of the invention. I, therefore, do not wish to be limited to the precise details of construction set forth, but desire to avail myself of such variations and modifications as come within the scope of 20 the appended claims.

Having described my invention what I claim as new and desire to secure by Letters Patent is:

1. In an attachment of the class described, 25 the combination of a housing; a rotary element mounted in said housing; a rotary grind stone detachably connected with said housing; an operative connection between said grind stone and one end of said rotary element; and resilient means for normally holding said grind stone in operative relation with said rotary element, substantially as described.

2. In an attachment of the class described, 35 the combination of a housing; a rotary element mounted in said housing; a bearing member detachably connected with said housing; a shaft mounted for rotary and longitudinal movement in said bearing member and adapted for operative engagement with said rotary element; and resilient means for normally holding said shaft in operative relation with said rotary element, substantially as described.

3. In an attachment of the class described, 45 the combination of a housing; a rotary element mounted in said housing; a bearing member detachably connected with said housing; a shaft mounted for rotary and longitudinal movement in said bearing member and adapted for operative engagement with said rotary element; and an elongated resilient yoke connected with said bearing member and pressing against the outer end 50 of said shaft for normally holding the latter in operative relation with said rotary element, substantially as described.

4. In an attachment of the class described, 60 the combination of a housing; a rotary element mounted in said housing; a bearing member detachably connected with said housing; a shaft mounted for rotary and longitudinal movement in said bearing member and adapted for operative engagement 65 with said rotary element; an elongated resil-

ent yoke connected with said bearing member and pressing against the outer end of said shaft for normally holding the latter in operative relation with said rotary element; and means for flexibly adjusting said yoke to adjust the pressure exerted thereby against said shaft, substantially as described.

5. In an attachment of the class described, 70 the combination of a housing; a rotary element mounted in said housing having an exteriorly projecting stud; a bearing member detachably connected with said housing; a shaft mounted for rotary and longitudinal movement in said bearing member and having a socket in one end adapted for engagement with said stud for operatively connecting said stud with said rotary element; means for holding said shaft in operative relation with said stud, said means comprising a resilient yoke engaging intermediate its ends against the outer end of said shaft; and an adjustable connection between the 80 ends of said resilient yoke and said bearing member, substantially as described.

6. In an attachment of the class described, 85 the combination of a housing; a rotary element mounted in said housing having an exteriorly projecting stud; a bearing member detachably connected with said housing; a shaft mounted for rotary and longitudinal movement in said bearing member and having a socket in one end adapted for engagement with said stud for operatively connecting said shaft with said rotary element; 90 means for holding said shaft in operative relation with said stud, said means comprising a cross piece on said bearing member; a resilient yoke engaging intermediate its ends against the outer end of said shaft; 95 and an adjustable connection between the ends of said yoke and said cross piece, substantially as described.

7. In an attachment of the class described, 100 the combination of a housing; a rotary element mounted in said housing having an exteriorly projecting stud; a bearing member detachably connected with said housing; a shaft mounted for rotary and longitudinal movement in said bearing member and having a socket in one end adapted for engagement with said stud for operatively connecting said shaft with said rotary element; means for holding said shaft in operative 105 relation with said stud, said means comprising a cross piece on said bearing member; a resilient yoke engaging intermediate its ends against the outer end of said shaft; an adjustable connection between the ends of 110 said yoke and said cross piece; a grind stone carried by said shaft; and a tank suspended 115 from said yoke and cross piece and inclosing the lower portion of said grind stone, substantially as described.

8. In an attachment of the class described, 120

- the combination of a housing; a rotary element mounted in said housing having an exteriorly projecting stud; a bearing member detachably connected with said housing; a 5 shaft mounted for rotary and longitudinal movement in said bearing member and having a socket in one end adapted for engagement with said stud for operatively connecting said shaft with said rotary element; 10 means for holding said shaft in operative relation with said stud, said means comprising a cross piece on said bearing member; bolts adjustably connecting the ends of said yoke and cross piece; a grind stone carried 15 by said shaft; and a tank inclosing the lower portion of said grind stone through the upper portion of which said bolts pass, substantially as described.
9. In an attachment of the class described, 20 the combination of a housing; a rotary element mounted in said housing having an exteriorly projecting stud; a bearing member detachably connected with said housing; a shaft mounted for rotary and longitudinal 25 movement in said bearing member and having a socket in one end adapted for engagement with said stud for operatively connecting said shaft with said rotary element; means for holding said shaft in operative 30 relation with said stud, said means comprising a cross piece on said bearing member; a resilient yoke engaging intermediate its ends against the outer end of said shaft; a pin
- on the outer end of said shaft engaging an opening in said yoke; and means connecting 35 said cross piece and yoke whereby the latter may be flexed to exert a pressure against said shaft, substantially as described.
10. In an attachment of the class de- 40 scribed, the combination of a housing open at one end and having a seat constituted therein; a rotary element mounted in said housing having a stud at the end thereof corresponding with the open end of said housing; a bearing member having one end 45 snugly fitting said seat; an annular keeper mounted on said housing adapted for engagement with said end of said bearing member to lock the same to said housing; a pin and slot connection between said hous- 50 ing and said bearing member for locking the latter against relative rotary movement; and a shaft rotatably mounted in said bearing member for locking the latter against relative rotary movement; and a shaft ro- 55 tatably mounted in said bearing member and operatively engaging with said stud, substantially as described.
- In testimony whereof I have signed my name to this specification in the presence 60 of two subscribing witnesses.

ARTHUR MITCHELL.
